UNITED STATES PATENT OFFICE.

JOHN M. WELCH, OF DES MOINES, IOWA.

PNEUMATIC SWIMMING BELT AND METHOD OF MAKING SAME.

Application filed November 11, 1922. Serial No. 600,283.

To all whom it may concern:

Be it known that I, JOHN M. WELCH, a citizen of the United States, and a resident of Des Moines, in the county of Polk and State of Iowa, have invented a certain new and useful Pneumatic Swimming Belt and Method of Making Same, of which the following is a specification.

The object of my invention is to provide a pneumatic swimming belt of simple, durable and inexpensive construction which may be packed and carried in a very small place when deflated, and when inflated it may be secured around the wearer's waist and both the inner and outer surfaces will remain substantially flat and parallel with each other, and substantially all of the expansion due to the inflation will occur at the top and bottom edges so that when the device is thus applied it will be firmly secured in position and at the same time will not interfere with the operator's movements in swimming or be likely to become dislodged from the wearer's body.

A further object is to provide an improved method of constructing a swimming belt of this class by which the results referred to in the foregoing statement of objects may be attained.

My invention consists in the construction, arrangement and combination of the various parts of the device, whereby the objects contemplated are attained, and in the process of making same, as hereinafter more fully set forth, pointed out in my claims, and illustrated in the accompanying drawings, in which:

Figure 1 shows a top or plan view of the swimming belt embodying my invention, with the ends connected as when in use.

Figure 2 shows a front elevation on an enlarged scale of the adjacent ends of the swimming belt connected with each other.

Figure 3 shows a central, longitudinal, sectional view through the end of the swimming belt containing the air valve.

Figure 4 shows an enlarged, transverse, sectional view on the line 4-4 of Figure 1; and

Figure 5 shows a sectional view on the line 5-5 of Figure 4, showing one edge member of the swimming belt partly disconnected from the adjacent side member.

Referring to the accompanying drawings it will be seen that my improved swimming

belt is circular in outline and has a general contour of a belt. Its walls are composed of four independent layers of material, each layer preferably consists of a woven fabric member and a thin rubber member vulcanized or otherwise secured to the fabric member.

The inner and outer member or walls of the swimming belt are indicated by the numerals 10 and 11 respectively, and each is made of a flat strip of the rubber coated fabric, with the weave or threads of the fabric extending longitudinally and transversely of the wall member, as shown in Figure 4. The outer one is of slightly larger diameter than the inner one.

The upper and lower wall members, 12 and 13 respectively, are each made of the same kind of fabric and rubber, but the weave of the threads is arranged on the bias, as shown in Figure 5. That is to say, the threads all run diagonally relative to the longitudinal axis of the member.

The edges of the top and bottom wall members are preferably made to overlap the outer surface of said wall members, and are firmly united to them.

In the manufacture of the parts of the swimming belt before described, I preferably proceed as follows:

The upper and lower wall members are cut from the woven fabric on the bias and then the edge thereof lies adjacent to the inner wall 10 and is made to overlap the inner wall as shown in Figure 4, and is secured thereto first by a row of stitches as indicated at 14, and this is done before the fabric is stretched in any way. Then after one edge has thus been secured, the remainder of the fabric is stretched out along its longitudinal center and the opposite edge is then overlapped around the outer wall 11 and permanently secured thereto, either by a row of stitches, as indicated at 15, or by vulcanizing or otherwise securing the parts together.

By means of this method of construction, the body of the swimming belt, when inflated to the proper degree, will assume the position as shown in Figure 4. That is to say, the inner and outer walls will be substantially flat and unwrinkled, and the upper and lower walls will be slightly arched and without wrinkles. When deflated, the inner and outer walls 10 and 11 will move toward each other, and when deflated the

2
swimming belt may be rolled into a very small space.

In Figure 5, I have shown one edge of the member 15 partly secured to the adjacent 5 side wall 11.

At each end of the swimming belt, the inner and outer walls are connected together and I preferably provide a vertically arranged stiffening bar 16 sewed between the inner and outer walls to prevent the end 10 portions from folding or wrinkling.

Both of these stiffening bars I have provided with eyelets to receive a tape 17 inserted in one end of the swimming belt and 15 communicating with the hollow interior thereof is an air valve 18.

In order to protect and conceal the air valve I preferably provide a fabric flap 19 secured at one end to the outer wall of the swimming belt, and provided with snap fasteners 20.

In practical use and when the swimming belt is deflated, it is obvious that it may be rolled upon itself into a very small and compact form.

When it is desired to use the swimming belt, it is partially inflated by inserting air through the air valve, and then placed around the wearer's waist, and the tape 17 is threaded through the eyelets and drawn so that the swimming belt makes a snug fit around the wearer's waist.

When this has been done the air pressure on the interior will cause the inner wall of the swimming belt to accurately fit around the wearer's waist. That is to say, the inner wall will be substantially straight up and down.

Furthermore, the outer wall will also assume a substantially straight up and down position and will be prevented from bulging outwardly at its horizontal central portion, due to the fact that the material of which it is formed has threads arranged longitudinally so it cannot stretch in that direction.

When inflated the upper and lower wall members by reason of the bias weave of the material will expand and assume substantially the position shown in Figure 4.

Obviously when the swimming belt has been securely laced to the wearer's waist, it cannot become detached by any movement of the operator within the water, and the operator may, if desired dive into the water 55 either head first or feet first without any danger of moving or altering the position of the swimming belt.

Furthermore, by reason of the fact that 60 the inner and outer walls are inflated and project outwardly from the wearer's body, only a slight distance, the swimming belt will not in any way interfere with the action of the operator's hands or arms in 65 swimming.

It is not necessary to deflate the swimming belt each time it is used, and on account of its construction of fabric lined with rubber, it will retain the air indefinitely.

By reason of my improved method of constructing the body of the swimming belt, it may be done cheaply and easily, and the upper and lower wall members will have the right shape and curvature to provide smooth surfaces when inflated, and at the same time the inner and outer walls may move toward and from each other and the fabric of the top and bottom wall members will expand and contract to the proper amount by reason of the fabric being composed of a layer of woven material cut on the bias and a layer of elastic rubber vulcanized to it.

I claim as my invention:

1. An improved pneumatic swimming belt of substantially circular form and composed of an inner wall formed of flat flexible material, an outer wall formed of flat flexible material and of slightly larger diameter, upper and lower walls connected to the edges of the inner and outer walls and capable of expanding when the inner and outer walls move away from each other, said parts being united to form a continuous air tight body closed at both ends, and means for connecting together the ends of the swimming belt.

2. In a pneumatic swimming belt, a body portion of substantially circular form comprising an inner and outer wall member, each made of flexible material but substantially inelastic as against strains applied longitudinally, and upper and lower wall members made of flexible material united to the inner and outer wall members and having a substantial degree of flexibility, said wall members forming an air tight compartment having closed ends, an air valve inserted therein, and means for connecting the closed ends together to be applied to the wearer's body.

3. An improved pneumatic swimming belt composed of an inner wall member comprising a woven fabric with the weave arranged longitudinally and transversely thereof, and a layer of elastic rubber, an outer wall member made of the same material, upper and lower wall members each made of a strip of woven fabric, the weave thereof being on the bias and a strip of elastic rubber, the edges of said wall members being permanently united, the ends thereof being closed, an air valve inserted therein, means for detachably connecting together the ends of the swimming belt.

4. An improved pneumatic swimming belt composed of an inner wall member comprising a woven fabric with the weave arranged longitudinally and transversely thereof, and a layer of elastic rubber, an

outer wall member made of the same material, upper and lower wall members each made of a strip of woven fabric, the weave thereof being on the bias and a strip of elastic rubber, the edges of said wall members being permanently united, the ends thereof being closed, an air valve inserted therein, means for detachably connecting together the ends of the swimming belt, and a vertically arranged stiffening bar at each end.

5. A method of making pneumatic swimming belts which consists in first providing

inner and outer wall members of woven fabric and rubber with one set of threads 15 running longitudinally thereof, then providing upper and lower wall members of woven fabric and rubber with the threads running diagonally, then permanently securing one edge of the fabric of the upper 20 or lower wall member to the adjacent inner wall member, then stretching the fabric longitudinally, and then permanently uniting it to the outer wall member after it has been stretched.

JOHN M. WELCH.
